(57) **CLAIM**

The ornamental design for a remote control, as shown and described.

DESCRIPTION

FIG. 1 is a perspective view of a remote control showing our new design;

FIG. 2 is a top view thereof;

FIG. 3 is a left side view thereof;

FIG. 4 is a right side view thereof;

FIG. 5 is a front view thereof;

FIG. 6 is a rear view thereof; and,

FIG. 7 is a bottom view thereof.

The broken lines in the figures indicate that the unshaded portion of the bottom of the control is not part of the claimed design and that the six small holes in FIG. 7 are also not part of the claimed design.
